(57) CLAIM

The ornamental design for an electronic scale as shown and described.

DESCRIPTION

FIG. 1 is a perspective view of an electronic scale showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and

FIG. 9 is an exploded view of the electronic scale;

FIG. 10 is a perspective view of the electronic scale where the electronic scale is in a configuration of use; and,

FIG. 11 is an enlarged view of portion 11 shown in FIG. 9. Referring to FIGS. 1, 7, and 9-10, the three shaded areas enclosed by the dot-dash-dot broken lines on the top of the main body of the electronic scale form part of the claimed design. The dot-dash-dot broken lines form no part of the claimed design. The shading within the three shaded areas represents an illuminated surface resulting in a contrast as compared to the area outside of the the three shaded area. The dash-dash broken lines within the three shaded areas in FIG. 10 depict environment that form no part of the claimed design. All other dash-dash broken lines in the drawings depict portions of the electronic scale that form no part of the claimed design.
